FLEXIBLE COPE

Chris K. Hansen, St. Paul, Minn.

Application October 25, 1937, Serial No. 170,832

1 Claim. (Cl. 22—157)

This invention relates to improvements in false copies such as used in the making of sand molds for casting metal in foundries.

In the present practice of casting metal the molten metal is poured into sand molds which have a cavity of the shape of the desired cast article and so that this metal fills the cavity and hardens therein to form the article after which the mold may be removed. The mold comprises two sections called the drag or bottom and the cope or top and these sections have in their meeting faces the impressions or recesses which together form the casting cavity of the desired shape and size. These impressions are formed by laying the pattern, which is of the same shape and size as the desired finished article, in an enclosing box or housing called a flask, blocking up the pattern so that it stands clear of the bottom of the flask and then sprinkling the molding sand into the flask so that it covers the pattern. The sand is then rammed and packed hard, the blocking removed, and the sand cut away in a flat plane down to a medial point of the pattern. This point of the pattern is called the parting line and must be determined according to the shape of the pattern so that no lateral projections thereof below the parting line will prevent drawing the pattern from the mold. The parting line or face of the mold is then smoothed with a suitable tool and this completes the drag or bottom section of the mold. A fine dust of suitable characteristics is then sprinkled over the face of the drag and the exposed part of the pattern. Sand is then placed in the flask and rammed solidly against the drag after which, by removing the flask, this top section of the mold called the cope may be removed and, due to the action of the dust aforesaid, will separate nicely from the drag along the parting line. The pattern may then be removed and when the drag and cope are placed together a cavity remains of the same shape and size as the pattern. This cavity may then be filled with the molten metal through what is called the sprue and when the metal hardens the casting may be removed and will be of the desired shape and size. The sprue referred to is a small hole formed in the cope of the mold and leading into the cavity therein or into gates which lead to other cavities where more than one article is cast in the same mold.

The foregoing process requires considerable time and labor as will be understood and in the attempt to reduce the time and labor of this kind of casting a false cope is used. This is in reality simply a cope made of some relatively rigid material and is formed by placing this material on

the pattern and completed drag and applying pressure so that the cope is formed with a cavity matching the exposed parts of the casting. With the cope thus prepared both the drag and cope may be made up as needed without the laborious and time consuming operation of facing off the drag to the parting line as hereinbefore described. This is made possible by first using the cope as a bottom section, placing it in the flask with the pattern in the impression and packing the sand against the plate and pattern. This forms the drag of the mold and of course as the cope is removed the parting line or face is left smooth and requires no tooling. Thereafter the cope is made in the usual manner against the drag and the work is carried out as described.

A great deal of difficulty has been experienced heretofore in making up these copies due to the fact that no suitable material has been found for this purpose. All materials now used have the extreme disadvantage of being relatively frangible and friable. As a result the copies after being used a short time begin to crumble and break away especially around the edges of the pattern impressions therein and when used in this condition the sand as it is packed in for the drag fills these crumbled portions. This sand then may remain on the drag when the cope is removed, may crumble and fall into the casting cavity, or may adhere to and be withdrawn with the pattern. When this excess of sand drops into the cavity it will of course form pits in the finished casting and when it crumbles away and is withdrawn with the pattern then it leaves a space around the pattern at the parting line which fills with metal and results in the formation of a fin or projection around the casting at this point. A great number of castings are thus spoiled and must be discarded while others require grinding and expensive finishing work to fit them for use.

With the foregoing facts in mind it is the primary object of my invention to provide a false cope having sufficient resiliency to prevent the edges from crumbling or breaking off and thus to ensure a sharp clean parting line at all times. By the use of false copies of this kind a very substantial saving will result, this being due to the fact that the now prevalent scrapping of very rough castings will be eliminated and the labor and materials used in grinding off the fins of the castings will be greatly reduced.

Another object is to provide a false cope of this kind made up of a tough, resilient and in-frangible material such as will retain its shape under the pressure exerted against it as the sand

is packed to form the mold drag and which will resist wear and breakage due to rough handling.

Still a further object is to provide a resilient false cope of the foregoing characteristics having reinforcing and mounting means whereby it will be given transverse and longitudinal rigidity and may be mounted in a frame to serve as a guide in its use in the flask.

The foregoing and other objects and advantages of the invention will be made apparent in the course of the following detailed specifications, reference being had therein to the accompanying drawings wherein:

Figure 1 is a plan or face view of a two-pattern false cope made in accordance with this invention, a corner portion thereof being broken away to disclose the reinforcing and mounting means for the false cope.

Figure 2 is an enlarged longitudinal and fragmental section along the irregular line 2—2 in Figure 1, the pattern being shown therein.

Figure 3 is a longitudinal cross section through a false cope made in accordance with this invention, showing the flask and a mold drag made up against the false cope and the patterns therein.

Figure 4 is a longitudinal section through a flask and mold drag, showing a false cope being made therein in accordance with this invention, the patterns being in place and a steam pressure plate being shown as in use in forming the false cope.

Referring now with more particularity to the drawings my improved false cope is designated generally at 5 and is of flat rectangular shape having the two pattern impressions or recesses 6 and 7 in its parting face 8. In the instance shown the false cope has two pattern impressions although any number of course may be used according to the nature of the article to be cast, and the patterns indicated at A and B are in the shape of, and designed to form, seed plates for corn planters. For this purpose the patterns include the center boss C, the annular tapering rim D, the connecting spokes or arms E, the pin F and other small parts which need not be referred to specifically since this form of pattern is shown only for purposes of exemplification. To accommodate these patterns, the false cope 5, as stated, has the spaced impressions 6 and 7 with the sloping sides 9 to accommodate the pattern rim D, the center socket or pocket 10 to receive the boss C and the radially extended grooves or valleys 11 to receive the spokes E so that the patterns will seat in the impressions down to the parting lines G on the pattern. It will be noted that above the parting lines G no part of the patterns project so as to form an obstruction to prevent drawing the sand drag from the false cope (as will be described) and the parting line is in all cases so located on the pattern that this condition will obtain.

In making the false cope the mold drag is prepared in the usual manner by blocking up the patterns A and B in the flask, packing the molding sand in the flask around the patterns and then facing off the sand down to the parting lines G. This drag, indicated at H in Figure 4, is then placed on a metal plate I, confined within a rectangular upstanding band or frame J which extends above the face of the drag some distance and placed in an oven and baked until hard. The parting face K of the drag is then filled in with plaster of Paris or other suitable material so as to be perfectly smooth, the patterns A and

B are replaced, and the composition or material used for the match plate is filled in within the band J. A hollow pressure pad or steam casting L is then pressed down on the material within the band J by action of the screw jack M and steam is passed through the pad to melt or soften the packed material causing it to flow around all parts of the patterns and become a compacted homogeneous mass. The pad L is then removed, the false cope allowed to cure and then removed ready for use. The exposed faces of the drag 4, patterns A and B and surrounding band J are all initially coated with some non-vulcanizing or non-melting material such as plaster of Paris to facilitate the removal of the finished plate.

The material or compositions used for the false cope may be rubber scraps or other suitable resilient tough matter of low melting point and in the process of filling in over the patterns a sheet 12 of reinforcing screen or mesh is placed so as to clear the patterns A and B and lie within the body of the completed cope. This sheet 12 serves to reinforce the cope as a whole against flexing motion either transversely or longitudinally and permits the use of comparatively coarse or cheap material for the body or back portion of the cope. The material used for the face of the cope however should be of a finer nature so as to present a smooth surface and have the necessary wear resistant and resilient qualities. To provide for mounting the finished plate washers 13 are placed around the corners and near the center line of the reinforcing plate 12 and pins 14 are placed in the drag H so that they will project upwardly through these washers and will form screw holes 15 through the finished cope as will be clearly evident.

When removed from the band J the false cope is mounted on a rectangular board 16 by screws 17 passed through the holes 15 and washers 13 into the board and the margins are confined within a frame 18 in the manner shown. This frame 18 carries projecting handles 19 which have guide apertures 20. In use then the cope thus mounted receives the patterns A and B in its impressions 6 and 7 and the flask top N is placed over the cope with the guide pins O through the apertures 20 after which the mold sand is rammed down into the flask to form additional mold drags 14 as required (Figure 3). When the false cope is removed it will be evident that the parting face of the drag will be left smooth and clear ready for making the cope (not shown) without any smoothing or tooling of any kind.

From the foregoing it will be apparent that I have provided a false cope which may be readily made up as required and which is of such resilient characteristics that it will retain its shape at all times and will not crumble or break away around the pattern impressions as so often occurs with other materials. The disadvantages resulting from this crumbling of the false cope have been pointed out hereinbefore and need no further description herein. The material used for the false cope should have about the same resiliency and hardness as the casing of an ordinary automobile tire, this being found to afford sufficient resiliency to prevent breaking off the edges of the pattern impressions while still making the false cope solid enough to prevent distortion when under pressure of the sand as it is packed to make the mold drag.

While I have herein set forth a certain preferred embodiment of my invention it is understood that I may vary from the same in details

within the scope of the appended claim. Having thus fully illustrated and described my invention, what I claim is new and desire to secure by Letters Patent is:

- 5 A false cope for making casting molds from patterns, the said cope being made of rubber heated and flowed around a pattern for forming a pattern impression in one face of the cope while

leaving the opposite face plane, a sheet of reinforcing material imbedded in the cope parallel with the plane face thereof, and the portion of the cope around the pattern impression being formed of rubber of fine texture while the portion strengthened by the reinforcing sheet is formed of a coarse and crude rubber. 5

CHRIS K. HANSEN.
